UNITED STATES PATENT OFFICE

CHARLES A. MOORE, OF EDINA, MINNESOTA

AIR CONDITIONING AND CIRCULATING APPARATUS

Application filed January 3, 1927. Serial No. 158,763.

My invention relates to improvements in air conditioning and circulating apparatus.

An object of the invention is to supply an apparatus for providing heated or refrigerated ventilation for an associated room or rooms and for reversely circulating air in such room or rooms, under heating or refrigeration.

Another object of the invention is to provide an apparatus, as above, through which air may be recirculated under heating or refrigeration.

An additional object of the invention is to provide an apparatus of the present kind wherein the structure is simple, durable and relatively inexpensive and which is efficient in operation and easily controlled to effect the desired results.

In the accompanying drawing, the single figure is a view mainly in vertical section, the same illustrating an embodiment of my invention.

Reference being had to the drawing it will be seen that a construction forming an enclosed space and a container for liquid beneath said space which opens thereinto, includes a tank 10 and a structure superimposing said tank, said structure comprising end walls 11 and 12, side walls 13 (only one shown) and a ceiling 14. Between the end walls 11 and 12 is a partition 15 dividing the interior of the structure into two chambers A and B, said portion 15 being formed with an opening 16 therein and constructed so that the lower portion thereof extends for some distance down into the tank 10. Said tank contains a quantity of liquid 17 the level of which is suitably maintained at an elevation slightly above the lower extremity of said partition 15. In other words, the lower extremity of said partition 15 is submerged in the liquid 17 in tank 10. And from this, it will be understood that said chambers A and B are shut off one from the other, except for the opening 16 in the partition 15.

Directed into chamber A from the outside of the structure is an air ingress pipe 18, the same throughout the greater part of its length, within said chamber, extending downwardly therein. Said pipe 18, opening at its

lower end slightly above the level of liquid 17 in tank 10, is encircled by an open ended case or jacket 19, the lower end of which dips slightly into said liquid in said tank. This jacket 19 is suitably supported in position about the pipe 18, as by means of a bracket 20 anchored to the end wall 12. A downwardly directed nozzle 21, located within the pipe 18, is supplied with liquid from a feed pipe 22 issuing from a pump 23, which takes its supply through an inlet pipe 24 leading thereto from tank 10. Said feed pipe 22 also supplies liquid from the tank 10 to a battery of downwardly directed nozzles 25 located in chamber B above the level of the opening 16 in partition 15. All of said nozzles 25 and the nozzle 21 spray liquid therefrom into the tank 10. A blower fan 26, mounted in the opening 16 in the partition 15 forces air from chamber A, through said opening 16, into chamber B and through the spray from the nozzles 25 therein. In chamber B, remote from said fan 26, is an eliminator 27 of conventional pattern, the same traversing the chamber B and serving in the usual manner, to catch any liquid carried with the air passing therethrough under the force of the fan 26. This eliminator 27 is situated with respect to the tank 10 so that any drain therefrom may gravitate back into said tank. On the side of the eliminator 27, opposite the fan 26, a feed duct 28 issues from the chamber. This feed duct 28 extends to and opens into a room or rooms (not shown) in which the air is to be conditioned. Extending back from such room or rooms is a return duct 29, the same opening into compartment A. In the drawing, I have shown the feed duct 28 issuing through the ceiling 14 and the return duct 29 also issuing through the ceiling 14, but it will be understood, of course, that said ducts may issue through either of the end walls 11, 12 or side walls 13.

Horizontally disposed within chamber B is the main reach 30 of an egress duct, one end of which projects through partition 15 and terminates in a downwardly extended reach 30a within chamber A, said reach opening 100

into the outer air through side wall 13. Said egress duct 30 extends through the eliminator 27 and on the side of said eliminator opposite the fan 26, said duct is supplied with two branch ducts 31 and 32, the former extending upward to a point near the ceiling 14 and the latter extending downward to a point near the floor portion 10^a of the structure at the rim of tank 10. Between said eliminator 27 and partition 15, said egress duct 30 is supplied with additional branch ducts 33 and 34, branch duct 33 extending upward to a point near the ceiling 14 and branch duct 34 extending downward to a point slightly above the rim of the tank 10. A cross duct 35 provides communication between the feed duct 28 and the chamber A, while a second cross duct 36 provides communication between the return duct 29 and the chamber B. Dampers are provided in the apparatus as follows: damper 37 in feed duct 28 between chamber B and point of connection of cross duct 35 with said feed duct, damper 38 in said cross duct, damper 39 in return duct 29 between chamber A and point of connection of cross duct 36 with said return duct, damper 40 in said cross duct 36, damper 41 in pipe 18 above nozzle 21, damper 42 in branch duct 31, damper 43 in branch duct 32, damper 44 in branch duct 33 and damper 45 in branch duct 34. Coiled within tank 10 is a pipe 46 through which a suitable medium is circulated to affect the temperature of the liquid 17 in said tank. In use, the pump 23 and blower fan 26 are put into operation. Heated or refrigerated liquid, as the case may be according to the nature of the medium circulated through pipe 17, is sprayed from the nozzle 21 in pipe 18 and from the nozzles 25 in chamber B. If the liquid is heated, the heating of the rooms associated with the apparatus will ensue and, if refrigerated, the refrigeration of said rooms will be effected. The simple heating or refrigerating of the associated rooms is accomplished without ventilation and without re-circulation of air in the apparatus by closing all of the dampers, except damper 37 in feed duct 28 and damper 39 in return duct 29. With the dampers thus adjusted, air is drawn from chamber A and forced through the spray from nozzles 25, thence through the eliminator 27 and out of chamber B through feed duct 28. In passing through chamber B, the air is washed and heated or refrigerated as the case may be. Passing from the feed duct 28 under the force of the blower fan 26, the conditioned air is circulated through the room or rooms in connection with said duct and impelled back to chamber A through return duct 29, thus completing the cycle. Fresh air is admitted to the apparatus and used air discharged therefrom by opening damper 41 in pipe 18 and one or more of dampers 42, 43, 44 and 45. With damper 41 open, fresh air is drawn into pipe 18 from the outside by the action of the spray from nozzle 21 and by suction from the blower fan 26, said air being washed and refrigerated or heated by contact with the spray in pipe 21, also in passing through the stratum of splashing liquid at the surface of liquid 17 within the jacket 19 and, further, in passing upward through jacket 19 into chamber A. Air is expelled to the outside by opening any one of dampers 42, 43, 44 and 45 in branch ducts 31, 32, 33 and 34. The provision made for selection of these dampers permits of a wide range of control in the expulsion of air from the apparatus, whereby warmer air at the ceiling or colder air at the lower portion of chamber B, at either side of the eliminator 27, may be forced to the outside. Under certain circumstances it may be desirable to reverse the circulation of the air in the room or rooms associated with my appliance, that is to say, to employ the feed duct 28 as a return duct and the return duct 29 as a feed duct. This condition is brought about by closing damper 37 in feed duct, opening damper 38 in cross duct 35, closing damper 39 in return duct 29 and opening damper 40 in cross duct 36. Air from chamber B then passes through cross duct 36 to duct 29, now the feed duct, and, in returning to the appliance comes back through duct 28, now the return duct, to cross duct 35, whence it issues into chamber A. Some of the air in the system may be re-circulated through the appliance to re-heat or additionally refrigerate the same by opening one or the other of dampers 38 and 40 in cross ducts 35 and 36, when dampers 37 and 39 in feed and return ducts 28 and 29 are open. With damper 40 in cross duct 36 open, air from chamber B is shunted back to chamber A. Likewise, when damper 38 in cross duct 35 is open, air is shunted back to chamber A from feed duct 28. Changes in the specific form of my invention, as herein disclosed, may be made within the scope of what is claimed without departing from the spirit of my invention. Having described my invention, what I claim as new and desire to protect by Letters Patent is:

1. In combination, a structure forming an enclosed space and a tank for a refrigerating liquid beneath said space opening thereto, a wall in said structure extended down into the tank, beneath the normal level of liquid therein, providing adjoining chambers in said space, a pipe extended downward from the outside into one of said chambers and terminating at its lower end above the surface of the liquid in said tank, an open ended jacket encircling said pipe and submerged at its lower extremity in the liquid in the tank,

- means for chilling said liquid in said tank, a nozzle in said pipe disposed to spray liquid downward therein, a damper in said pipe above said nozzle, a nozzle in the other chamber disposed to spray liquid downward into said tank, a pump in piped communication with said tank and with said nozzles for pumping liquid from the tank to the nozzles, said wall having an opening therein at an elevation beneath the nozzle in said second chamber, a fan for blowing air from the first chamber, through said wall opening, into the second chamber and through the spray from the nozzle in said latter chamber, an eliminator at the side of said nozzle opposite said fan, a feed duct issuing from said second chamber on the far side of said eliminator, a return duct communicating with said first chamber, a cross-duct providing communication between the second chamber and said return duct, a damper in said cross-duct and a damper in the return duct between said first chamber and the junction between said cross-duct and return duct, a second cross-duct providing communication between said feed-duct and said first chamber, a damper in said second cross-duct and a damper in the feed-duct between said second chamber and the junction between said feed-duct and said second cross-duct, an egress duct opening to the outside and having a reach thereof extended through said second chamber, valved branch ducts on opposite sides of the eliminator extending upward from said reach and opening near the ceiling of the second chamber, and valved branch ducts also on opposite sides of said eliminator extending downward from said reach and opening near the floor of said second chamber and above the liquid level in said tank.
2. In combination, a structure forming an enclosed space and a tank for a refrigerating liquid opening into said space, a wall in said structure extending downward into the tank beneath the normal level of liquid therein providing adjoining chambers in said space, a pipe extending downward into one of said chambers from the outside and terminating at its lower end above the surface of the liquid in said tank, a nozzle in said pipe disposed to spray liquid downward therein, a nozzle in the second chamber disposed to spray liquid downward into said tank, a pump in piped communication with said tank and with said nozzles for pumping liquid from the tank to the nozzles, said wall having an opening therein at an elevation beneath the nozzle in said second chamber, a fan for blowing air from the first chamber, through said wall opening, into the second chamber and through the spray from the nozzle in said latter chamber, an eliminator at the side of said nozzle opposite said fan, a feed duct issuing from said second chamber on the far side of said eliminator, a return duct communicating with
- said first chamber, and an egress duct leading from the second chamber to the outside.
3. In combination, a structure forming two adjacent chambers, means for blowing air from one chamber into the second chamber, means within said second chamber for affecting the air entering the same, a feed duct issuing from said second chamber, a return duct communicating with said first chamber, a cross-duct providing communication between the second chamber and said return duct, a damper in said cross-duct and a damper in the return duct between said first chamber and the junction between said cross-duct and return duct, a second cross-duct providing communication between said feed-duct and said first chamber, a damper in said second cross-duct and a damper in the feed-duct between said second chamber and the junction between said feed-duct and said second cross-duct.
4. In combination, a structure forming a chamber, a conduit leading into said chamber, a fan associated with said conduit for impelling air into said chamber, means within the chamber for affecting the air entering the same, a feed duct leading from said chamber for conducting air to a remote point of use, a return duct leading from said point of use to said conduit, and two cross ducts, one leading from said chamber to the return duct and the other from the feed duct to said conduit to shunt air back to said chamber before using the same.
5. In combination, a structure forming a chamber, a conduit leading into said chamber, a nozzle disposed in said chamber to spray liquid therein, a fan associated with said conduit for impelling air into said chamber through the spray from said nozzle, an eliminator in the chamber on the side of said nozzle opposite to said fan, a feed duct leading from the chamber on the far side of the eliminator, a return duct leading to said conduit, means of ingress for fresh air to said conduit, and means of egress for air from said chamber at either side of said eliminator.
6. In combination, a structure forming a chamber, a conduit leading into said chamber, a nozzle disposed in said chamber to spray liquid therein, a fan associated with said conduit for impelling air into said chamber through the spray from said nozzle, an eliminator in the chamber on the side of said nozzle opposite to said fan, a feed duct leading from the chamber on the far side of the eliminator, a return duct leading to said conduit, means of ingress for fresh air to said conduit, and means of egress for air from both upper and lower portions of said chamber on both sides of said eliminator.
7. In combination, a structure forming a

chamber, a conduit leading into said chamber, a fan associated with said conduit for impelling air into the chamber, means within said chamber for affecting the air entering the same, a feed duct leading from said chamber, and a cross duct leading from said chamber to said conduit for recirculating air in said chamber before the same is expelled into said feed duct.

8. In combination, a structure forming a chamber, a tank at the lower portion of said chamber for a quantity of liquid, a pipe extending downward from the outside into said chamber, the lower end of said pipe terminating above the surface of the liquid in the tank, an open-ended jacket encircling said pipe and submerged at its lower extremity in the liquid in the tank, means in said tank independent of said jacket, for chilling the liquid in the tank, a nozzle in the pipe directed to spray liquid downward therein, means for pumping liquid from said tank to said nozzle, and means of egress for air from said chamber.

25 In testimony whereof, I have signed my name to this specification.

CHARLES A. MOORE.
